UNITED STATES PATENT OFFICE.

CHARLES TWEEDIE, OF JEFFERSON CITY, MISSOURI.

PROCESS OF MAKING SHOES.

1,230,954.

Specification of Letters Patent. Patented June 26, 1917.

Application filed March 6, 1915. Serial No. 12,507.

To all whom it may concern:

Be it known that I, CHARLES TWEEDIE, a citizen of the United States, and a resident of Jefferson City, in the county of Cole 5 and State of Missouri, have invented a new and useful Improvement in Processes of Making Shoes, of which the following is a specification.

The invention relates to welt shoes, and 10 particularly to the manner of forming the shoe and of securing the sole of the shoe to the upper.

Objects of this invention are to make 15 shoes without using lasts, and to save material, machinery and labor heretofore required for machine made shoes. Further objects of the invention are to secure flexibility and comfort in machine made welt shoes.

Generally stated, the invention consists in 20 a new process for making welt shoes without insoles, and in improved shoes made by said process, but no claim for the shoes apart from the process is made herein.

What the invention consists in, and the 25 advantages thereof over shoes as heretofore made, appear more fully in connection with the following description of the processes of making shoes illustrated in the accompanying drawings. The invention is more 30 particularly defined in the appended claims.

In the drawings, wherein the same reference characters designate like parts in the several views,

Figure 1 is a perspective top view of a 35 shoe upper made in conformity to the invention;

Fig. 2 is a similar view of another form 40 of shoe upper made in conformity with the invention;

Fig. 3 is a perspective bottom view of the shoe upper shown in Fig. 1, showing the upper and welt turned in ready for the sole to be applied;

Fig. 4 is a view similar to Fig. 3 of the 45 upper shown in Fig. 2;

Fig. 5 is a top plan view of the shoe upper shown in Fig. 1 after the sole is cemented on and prior to stitching it to the welt;

Fig. 6 is a view similar to Fig. 5 of the 50 shoe upper shown in Fig. 2 after cementing on a three-quarter length sole;

Fig. 7 is a side view of a finished shoe embodying an upper like that shown in Fig. 2;

Fig. 8 is a side view of a finished shoe 55 embodying an upper like that shown in Fig. 1;

Fig. 9 is an outline view of the two parts of a shoe counter forming part of the invention;

Fig. 10 is a perspective view of the 60 counter;

Fig. 11 is a perspective view of a box toe forming tool for use in connection with the invention; and

Fig. 12 is a similar view of a modified 65 form of box toe forming tool.

In carrying out this invention, the shoe upper is prepared from the same patterns in use heretofore, with the same allowances for laps and seams, but the allowance for 70 lasting under at the sole is made less than has been required heretofore. The lasting allowance at the toe for the upper 13 shown in Fig. 1 is about from one-eighth of an inch to three-sixteenths of an inch, and this 75 allowance is substantially uniform for the entire length of the inside of the shoe to the heel seam and nearly around to the ball of the foot on the outside. The lasting allowance increases as the ball of the foot is approached, to a maximum of about from three-sixteenths of an inch to five-sixteenths of an inch, and gradually diminishes from the ball of the foot toward the toe, where it is about from one-eighth of an inch to 80 three-sixteenths of an inch.

The lasting allowance for the upper 14 shown in Fig. 2 is the same as that for Fig. 1 except around the heel, where it is from one-half to five-eighths of an inch, which is 85 about the same as for shoes made according to processes in common use heretofore. There is a considerable saving in the amount of leather required for the upper cut as above described over that required for uppers cut with a uniform lasting allowance of five-eighths of an inch, or thereabout, as has been required heretofore.

A leather counter 15 is fitted and sewed to the upper 13 prior to fitting the lining. This 100 counter may be of ordinary shape and construction, but it is preferably made in two pieces 15^a and 15^b (see Fig. 9) which are skived all around their edges and are sewed together at the back line of the heel, as 105 shown in Fig. 10. The two parts of the counter need not be sewed together separately, but may be connected by the same line of stitches which secures the two quarters together along the back seam. The 110 sewed edges of the two parts of the counter should be spread apart and the joint rubbed

down smooth. A back stay may be sewed to both the upper and the counter, thereby stiffening the joint between the two pieces 15^a and 15^b and strengthening the counter 5 and shoe at the heel. The lower edge of the counter may be slashed or notched to give it pliability. The counter 16 for the upper 14 (shown in Fig. 2) is similar to the counter 15, but it is slightly wider, the extra 10 width turning under the heel with the extra lasting allowance on the heel portion of the upper 14.

If desired, the counter 15 can be made somewhat wider than as shown in Fig. 1 15 and allowed to project from three-eighths to one-half of an inch below the lower edge of the upper. The projecting portion turns under the heel with the lower edge of the upper and forms a flange which is wide 20 enough to be sewed or nailed to the sole inside of the vertical wall of the heel to strengthen the heel portion of the shoe. Also, if desired, the lasting allowance of the upper 14 around the heel can be made the same 25 as around the greater portion of the sole, that is, just enough to turn under, and the counter can be arranged to project below it to provide a sufficient width for lasting under. Preferably a line of stitching is run 30 around the heel seat to secure the counter to the upper. In the drawings this line of stitching is shown as a continuation of the stitching 19 which secures the welt 17 to the upper, as is hereinafter described, but 35 the counter may be stitched around the heel seat separately if preferred. If a lining is used it is preferably secured by stitching the vamp to the quarters through the lining and if a toe cap or tip is used it is preferably 40 stitched to the vamp through the lining.

A welt or narrow strip of leather 17, about three-eighths to one-half an inch in width is sewed to the lower edge of the upper 13 all the way around it. In sewing the welt 45 to the upper the grain side of the welt is laid flatwise on the finished outside face of the upper, with the outer or lower edges of the welt and upper coextensive, and a line of stitching 19 at a uniform distance from 50 the edge of the upper of from one-eighth to three-sixteenths of an inch is run through the welt, upper and lining 20. This stitching of the welt to the upper is flat work and can be done by girl operatives on ordinary 55 sewing machines.

The upper 14 has a welt 18 which extends from about opposite the breast of the heel on the outside around the toe to the corresponding point on the inside of the shoe (see 60 Fig. 2). The welt 18 for the upper 14 is like the welt 17 for the upper 13 in all respects except its length, and is likewise stitched through the upper and lining 20.

The lining 20 is not necessary for all 65 shoes, and it may be wholly or partly omit-

ted if desired. The lapped edges of the welt, upper and lining are cut with slashes or notches 21 around the periphery of the heel and toe portions to expedite turning the welt. These notches may be omitted in 70 part or entirely, depending upon the thickness of the leather and the sharpness of the curves in the outline of the shoe.

The next operation in making the shoe, shown in Figs. 2, 4, 6 and 7 is inserting a 75 heel seat 22, which may have a short shank portion, turning in the lower edge of the heel portion of the upper, counter and lining under the heel seat, and tacking the flange 23 thus formed to the heel seat (see 80 Fig. 4). This operation may be performed on an iron horn shaped to conform approximately to the size and shape of heel desired. The shank portion of the insole may be stiffened by means of an arch support 24 85 consisting of a strip of thin spring steel, wood or other suitable material.

The outsole is rounded off to approximately its desired finished shape prior to attaching it to the upper. One or two strips 90 of canvas 25 are impregnated with hardening gum and are pasted between the upper and to the lining in the toe, then the free edge of the welt is pulled away from the upper and turned out all around, thereby 95 turning in the sewed edges of the welt, upper and lining. The exposed face of the welt is glued or pasted to the edge of the flesh side of the outsole, following the outline of the sole all the way around the shoe 100 from the heel end of the sole on the inside to the heel end of the sole on the outside. A wood or fiber-board form 26 for the box toe (see Figs. 11 and 12) may be inserted in the toe, either before or after pasting the welt 105 to the sole. If a box toe is not desired, the strips of canvas 25 may be omitted and the form 26 may be dispensed with.

The outsole 27 for the shoe shown in Figs. 5 and 8 is cut full length, with the 110 same allowance for extension beyond the upper all the way around the shoe. The outline of the outsole is what determines the shape of the shoe in the case of the shoe shown in Figs. 5 and 8. The outsole 28 for the shoe shown in Figs. 6 and 7 may be cut full length, but preferably it is three-quarter 115 length, and the shank end is skived off and overlaps the breast of the heel, as is more fully described in my patent No. 1,115,038, 120 dated Oct. 27, 1914. The shape of the fore-part and shank of the shoe shown in Figs. 6 and 7 is determined by the outline of the sole, and the shape of the heel is determined by the outline of the heel seat 22.

Following the pasting down of the welt, the outsole and welt are sewed together by a line of stitching 29 following the contour of the sole around the outside of the upper. This stitching operation can be per- 130

formed on any machine for fair-stitching soles, and does not require a special machine such as has been required heretofore for stitching the upper to the sole or insole.

5 The shoe is next fitted with a heel, the sole and heel are trimmed, the toe and heel portions of the upper are smoothed or ironed, and the bottom of the shoe and edges of the sole and heel are painted, according 10 to existing processes for finishing shoes as may be desired. The shoe shown in Fig. 7 is preferably fitted with a heel 30 having a sole extension portion for piecing out the short sole 28, in accordance with my patent No. 15 1,115,038; but this invention is not restricted to any particular heel or process of attaching it. The shoe shown in Fig. 8 may have a leather or rubber heel 31, or the heel 20 may be omitted, as desired. The box toe form 26 may be fitted with a pivoted connecting link 32 and heel piece 33, as shown in Fig. 11; or it may be fitted with a pivoted shank 34 having a pointed tool 35 in its free end for engaging the sole and retaining the form in position, as shown in 25 Fig. 12.

Among the advantages of the invention are the saving in cost of production through the elimination of lasts, insole patterns, in- 30 soles, labor in connection with tacking on insoles and outsoles for lasting and inseam- 35 ing machines, pulling lasts, and rough trimming soles; the saving in royalties for pulling over machines, lasting machines, inseam- 40 ing machines and stitching machines; the saving in upper leather and lining material; and the further saving in the cost of the leather due to the fact that cheaper upper leather can be used than is practicable for 45 lasted shoes. A shoe made in accordance with the invention is more substantial and serviceable than a turn shoe and more flexible and more comfortable than a stitch down shoe, and it is cheaper than either.

50 The invention is not restricted to the exact operations heretofore described, nor to their order of performance. It is evident that changes in the shape and arrangement of some of the parts of the shoe can be made 55 without departing from the invention, and the invention is not restricted to the particular shoes shown and described.

I claim the following as my invention:

1. The process of making welt shoes which 60 comprises making the upper and rounding the sole substantially to its finished shape, sewing a welt along the bottom edge of the upper on its outer side, turning the upper edge of the welt out and securing it flatwise 65 on the top margin of the shaped sole following the outline thereof to determine the entire outline of the welt and the bottom portion of the upper in contact therewith.

2. The process of making welt shoes which 70 comprises stitching a counter to an upper

along the location of the back seam and heel seat, sewing a welt along the bottom edge of the upper on its outer side, turning in the heel seat portion of the upper and counter, turning the upper edge of the welt 75 out and securing it flatwise on the top margin of a sole shaped to substantially its finished shape following the outline thereof to determine the entire outline of the welt and the bottom portion of the upper in contact 75 therewith as far as the two are coextensive.

3. The process of making welt shoes which comprises making the upper with a small lasting allowance around the toe and inside of the shank and a larger lasting allowance 80 along the ball on the outside, sewing a welt along the bottom edge of the upper on its outer side, turning the upper edge of the welt out and securing it flatwise in coincidence with the edge of a sole previously 85 rounded to substantially its finished shape.

4. The process of making welt shoes which comprises making the upper and rounding the sole substantially to its finished shape, sewing a welt along the bottom edge of the 90 upper on its outer side, notching a portion of the bottom edge of the welt and upper, turning the upper edge of the welt out and securing it flatwise to the edge portion of the rounded sole with their edges in coincidence. 95

5. The process of making welt shoes which comprises making the upper, sewing a counter to the heel portion of the upper and a welt along the bottom edge of the 100 upper on its outer side, turning the upper edge of the welt out and the lower edge of the welt and counter in, and securing the bottom of the welt flatwise to the sole with their edges in coincidence, said sole having 105 previously been rounded to substantially finished shape and securing a heel to the turned under portions of the counter and welt.

6. The lastless process of making shoes which comprises cutting the upper with a 110 uniformly small lasting allowance around the toe and shank, sewing a narrow welt flatwise along the lower edge of the upper, turning the inner edge of said welt out whereby the lower edge of said upper is 115 turned in, outlining the contour of the shoe on the sole, as by rounding the sole to substantially finished shape, and securing the outturned edge of said welt to the sole in coincidence with said contour to shape the 120 shoe around the bottom of the upper.

7. The lastless process of making shoes which comprises cutting the upper with a uniformly small lasting allowance around the toe and shank, sewing a narrow welt 125 flatwise along the lower edge of the upper, the lower edges of said welt and upper being parallel and the face sides of said upper and welt being placed together, turning the inner edge of said welt out whereby the lower 130

edge of said upper is turned in, outlining the contour of the shoe on the sole, as by rounding the sole to substantially finished shape, and securing the outturned edge of said welt to the sole along said contour to shape the shoe around the bottom of the upper.

8. The lastless process of making shoes which comprises cutting the upper with a uniformly small lasting allowance around the toe and shank and a slightly larger lasting allowance at the ball on the outside, sewing a narrow welt flatwise along the lower edge of the upper, turning the inner edge of said welt out whereby the lower edge of said upper is turned in, outlining the contour of the shoe on the sole, as by rounding the sole to substantially finished shape, and securing the outturned edge of said welt to the sole along said contour to shape the shoe around the bottom of the upper.

9. The lastless process of making shoes which comprises cutting the upper with a uniformly small lasting allowance around the toe and shank, sewing a narrow welt flatwise along the lower edge of the upper on its face side with the outer edge of said welt coextensive with the lower edge of the upper, turning the inner edge of said welt out whereby the lower edge of said upper

is turned in, outlining the contour of the shoe on the sole, as by rounding the sole to substantially finished shape, and securing the outturned edge of said welt to the sole along said contour to shape the shoe around the bottom of the upper.

10. The lastless process of making shoes which comprises cutting the upper with a uniformly small lasting allowance around the toe and shank and a slightly larger lasting allowance at the ball on the outside, sewing a narrow welt flatwise along the lower edge of the upper with the outer edge of said welt coextensive with the lower edge of the upper, the face sides of said upper and welt being placed together, turning the inner edge of said welt out whereby the lower edge of said upper is turned in, outlining the contour of the shoe on the sole, as by rounding the sole to substantially finished shape, and securing the outturned edge of said welt to the sole along said contour to shape the shoe around the bottom of the upper.

Signed at Jefferson City, Missouri, this 26th day of February, 1915.

CHARLES TWEEDIE.
